A. L. Brook,
Wood Planing Machine.
Patented Jan. 7, 1835.

Jan 7. 1895

9.

Artemas S. Brooks, Somerville, Mass.

Sectors Patent dated Jan 7, 1895.

The subscriber opposite to in these Sectors Patent and making part of the same containing a description in the words of the said Artemas S. Brooks himself of his improvement on the machine for planing boards patented by William Woodworth.

To all whom it may concern.

It is known that Artemas S. Brooks of Somerville in the County of Middlesex and Commonwealth of Massachusetts have invented a new and useful improvement in the machine patented by William Woodworth for planing long narrow and narrow boards on the 29th day of December 1828 and I do hereby declare that the following is a full and exact description of my said improvement.

In the machine as patented by Woodworth one side only of a board or plank could be planed at one stroke in running case, is all that is necessary; there are others however as in board for packing boxes partitions and various other purposes, it is necessary that both sides should be planed. To effect this I employ a second rotary cutting wheel made in all respects like that already in use in the said machine, but so placed that it may operate on the under side of the board opposite to that on which the first cutter wheel acts.

The second cutter wheel I fix in a frame adjustable by screws wedges or otherwise so that it may be adjusted to the thickness of the stuff to be planed.

The mode of working the machine to ash advance the board against the cutter is to be the same with that already followed.

All that I claim as my improvement being the employment of the cutter wheel for the purpose of planing both sides of a board or plank at the same time in the manner herein before set forth, employing a double belt or any other convenient mode for giving motion to the said cutter wheel.

Witnessed
